CLAIM

We claim, the ornamental design for a lighting apparatus, as shown and described.

DESCRIPTION

FIG. 1 is a top right side perspective view showing my design;

FIG. 2 is a bottom perspective view thereof;

FIG. 3 is a top elevational view thereof;

FIG. 4 is a bottom elevational view thereof;

FIG. 5 is a front elevational view thereof;

FIG. 6 is a rear elevational view thereof;

FIG. 7 is a left side elevational bottom plan view thereof;

and,

FIG. 8 is a right side elevational view thereof.
